UNITED STATES PATENT OFFICE.

CHARLES L. KIDDER, OF NEW BRUNSWICK, NEW JERSEY, ASSIGNOR TO THE MOTOR SEWING MACHINE COMPANY, OF NEW YORK.

SPRING-MOTOR.

SPECIFICATION forming part of Letters Patent No. 307,309, dated October 28, 1884.

Application filed May 3, 1884. (No model.)

To all whom it may concern:

Be it known that I, CHARLES L. KIDDER, a citizen of the United States, residing at New Brunswick, in the county of Middlesex and State of New Jersey, have invented certain new and useful Improvements in Spring-Motors, of which the following is a full, clear, and exact description, reference being had to the accompanying drawings, and to the letters 10 of reference marked thereon, which form part of this specification.

Figure 1 is a front view of the entire machine; Fig. 2, an end view of the left-hand end of machine; Fig. 3, a top view of bearing-frame 15 removed from the machine and supporting the winding-cylinder, winding-shaft, bevel-wheels, and stop-work mechanism. Fig. 4 is an enlarged view of friction device used when winding by the foot of the operator; Fig. 5, a sectional view of the same; Fig. 6, an enlarged 20 view of center of wheel C, with the friction-pawl, the hub in which the pawl is held, and the manner of fastening the same to the shaft. Fig. 7 is an enlarged view of the mechanism 25 by which I increase or diminish the tension of the spring.

The legs or standards A A, with the table B, constitute the frame of the machine. In the frame is fixed the bearing-frame shown in Fig. 3, upon which are supported the winding-shafts a and b. Through the frame below the bearing-frame passes the shaft d. On the frame, as shown in Fig. 2, is hung the pendent lever G, with a foot-rest at its lower end 35 and having attached to it two connection-bars, I and H.

The bar I, in connection with the pendent lever and the mechanism shown in Fig. 4, provides an easy and noiseless method of winding 40 by the foot of the operator or of renewing at intervals the power already expended in running the machine, and the bar H, when connected with the crank e, providing a simple means of running the machine by foot-power 45 when by reason of breakage of the motor or for any other reason it is not desired to use the motive power of the spring.

The motive power of the machine is a coil-spring, D, contained within the fusee w, and 50 having one end attached to the inside of the

fusee, while the other is solidly connected with the shaft d. This shaft d is kept in position by the device shown in Fig. 7, by means of which, also, the tension of the spring can be increased or diminished, as may be desired. 55 Upon the fusee or drum is wound a small cord, which is fastened at its other end to the winding-cylinder E. Said cylinder E is actuated by means of its connection by friction-clutch u, (shown in Fig. 6,) to a winding-shaft 60 adapted to be revolved by a crank fitted upon either end. The winding-cylinder can also be revolved by means of the foot winding apparatus shown in Fig. 3, and it is prevented from being wound too tightly by means of the safety 65 stop mechanism (shown in Fig. 3) r and p.

The principal features in this mechanism have already been patented to me. The novel features are the new method of winding by means of the foot-lever G and the connected 70 parts.

The operation of renewing the power by the use of my improvement is as follows: The foot of the operator is placed upon the foot-rest g of the pendent lever G, and the pendent lever 75 is swung toward him. This motion brings the spring h to bear upon the pin i, which is made fast in the friction-pawl j, thus making a connection between it and the inside periphery of the wheel F, which is made fast to the shaft 80 b. The pendent lever G is now swung away from the operator, thus turning the wheel F, the shaft b, the bevel-wheels k and l, the winding-cylinder E, and by means of the cord winding the spring contained in the spring-box D. 85 Upon stopping the pressure of the foot against the pendent lever G the small spring m (shown by dotted lines in Fig. 4) swings the friction-pawl j forward and away from the inside periphery of the wheel F, leaving it free to turn 90 by the action of the driving-spring. It is to be particularly noticed in this connection that, unlike friction-clutches now in use, my device turns the wheel F in one direction and then instantly allows it to turn back again in the opposite direction, whereas the common friction-clutch is adapted simply to turn a wheel continuously in one direction. This operation continued gradually rewinds the spring. 95

The second improvement consists of the 100

crank *e* on the end of the driving-shaft *o*, and the connection-bar *H*, attached to the pendent lever *G*, and adapted to connect the crank *e* with the pendent lever, and form a simple 5 method of running the machine by foot-power, the spring being entirely disconnected. The length of the bar *H* is such as to prevent the bar *I* from coming back so far as to form a connection between the friction-pawl *j* and the 10 wheel *F* when the machine is being run by foot-power.

Having thus set forth my invention, what I claim as new, and desire to secure by Letters Patent of the United States, is—

15 1. In a spring-motor, a friction-clutch having a lever impinging against the periphery of the wheel to be revolved and adapted to give such wheel a forward movement when desired and to permit its backward movement 20 as soon as the forward movement of the clutch and wheel have ceased, substantially as described.

2. In a spring-motor, a shaft connecting the driving-wheel with the mechanism operated 25 by the motive-spring thereof so as to cause such wheel to be driven thereby, and also adapted to communicate motion to the driving-wheel from a power independent of the spring-power of the mechanism, substantially as described.

30 3. In a spring-motor, the combination, with the pendent lever, of a winding apparatus adapted to be operated by means of a friction-clutch, substantially as set forth.

4. In a spring-motor, the combination of a

connecting-shaft having at one end a driving-wheel, devices constituting suitable means of connection to the motive power of the mechanism, a pendent lever, and devices constituting suitable means of a connection between such lever and a shaft so arranged that motion 35 may be imparted to the driving-wheel through 40 such pendent lever independently of the motive power of the mechanism, all substantially as described.

5. In a spring-motor, the combination of a 45 fusee containing a spring-box, a spring connected at one end to such box and secured at the other to a shaft, a winding cord or belt, a winding-cylinder, a friction-clutch adapted to actuate the winding-cylinder, and devices 50 constituting the means for connecting such clutch with a pendent lever, whereby the whole combination can be operated, substantially as set forth.

6. In a spring-motor, a connecting-shaft having at one end a driving-wheel, and adapted at the other end to receive motion from a vibrating pendent lever through proper devices constituting the means of connection, a gear-wheel adapted to revolve said connecting-shaft, 55 a winding-cylinder, winding-shaft, a belt or cord, a fusee or drum containing a spring-box and spring connected thereto, all substantially as described.
